UNITED STATES PATENT OFFICE

JAMES G. JOHNSTON, OF ATTLEBORO, MASSACHUSETTS

COLLAPSIBLE TUBE

Application filed August 25, 1930. Serial No. 477,491.

My invention relates to improvements in collapsible tubes and includes the provision I believe for the first time of a flexible protective sheaf therefor and a novel type of dispensing cap member which assists in holding the sheaf to the tube.

Collapsible tubes when used to hold shaving cream, cosmetics, toothpaste, etc., do not at the present time present a very attractive 10 appearance.

An object of my invention therefore is to provide an ornamental protective sheaf therefor which will enhance the beauty of the collapsible tube when used in milady's toilet or bag. It is apparent that the sheaf also assists in protecting the walls of the tube which are often of very frangible material. I provide an open lower end so that the sheaf may be readily removed from or attached around the 20 tube.

A further object of my invention is to provide a novel type of cap member for the tube which does not have to be completely unscrewed from the tube before the actual dispensing of the contents thereof takes place, but which has a portion which may be detachably secured around the nozzle and a portion rotatable thereon so that on a mere half or total revolution of said rotatable portion 25 the contents of the tube may be readily dispensed.

These and such other objects of my invention as may hereinafter appear will be best understood from a description of an embodiment thereof such as is shown in the accompanying drawing.

In the drawing, Fig. 1 is a perspective view of a collapsible tube having my invention attached thereto.

Fig. 2 is a disassembled perspective view of the various component parts of my invention, showing the usual collapsible tube cap being removed from the collapsible tube, the sheaf in the position it will take around the collapsible tube and my improved cap member in the position it will take when attached to the nozzle.

Fig. 3 is a sectional view of an end of the collapsible tube showing the two portions of 50 my improved cap member relatively rotated

so that the open portions thereof will be in alignment to permit dispensing of the contents of the tube.

Fig. 4 is a sectional view generally similar to Fig. 3, but with the portions of the cap 55 rotated to seal the tube to prevent dispensing of the contents thereof.

In the drawing, wherein like characters generally indicate like parts throughout, 10 generally indicates the collapsible tube, which 60 may be filled with tooth paste, paint, cosmetics, shaving cream, or any other desired material. Said tube 10 is normally provided with a central dispensing nozzle 12 usually externally threaded as at 14 and said tube 10 65 normally has the cap 16 for closing the same which is suitably internally threaded so that it may be threaded onto the threads 14 on the exterior of the nozzle 12.

I provide a protective sheaf 18 for said 70 tube. Said protective sheaf 18 includes the rigid top member 20 having a central nozzle opening 21 and adapted to abut the top of the tube 10 exterior of said nozzle 12 and a protective sheaf portion 22 of flexible material, 75 preferably woven wire or link mesh although it is obvious that any suitable type of protective, flexible ornamental material may be employed, enclosing the sides of said tube and open as at 23 at its lower end for insertion of 80 the tube therein.

I also preferably provide in association with said protective sheaf 18 a dispensing cap member 24 which includes a portion 26 preferably internally threaded as at 28 adapted to be permanently threaded on to the external threads 14 of said nozzle 12 and preferably arranged as shown in Figs. 3 and 4 to have the lower end 30 thereof about the top sheaf member 20 around said nozzle 12 to secure 90 said sheaf to said tube. Said threaded member 26 is also preferably provided with a dispensing slot 32 in the side wall 34 thereof above said nozzle 12 when said member is threaded thereon. Said cap member 24 also includes the member 36 having the side walls 38 adapted to surround said threaded portion 26 rotatably secured to said threaded portion in any desired manner preferably by means 95 of the rivet 39 insertable from inside said 100

members through cooperating holes 40 and 42 in said threaded and rotatable members to have the head 44 on the inside thereof so as to permit the end 46 to be countersunk in the outer surface 48 of said rotatable member. Said rotatable member has portions 50 of the side wall thereof open to dispense the contents of the collapsible tube 12 through the channel 52 formed when the open portion 10 50 of the side wall 38 of the rotatable portion 36 is brought into alignment with the slot 32 in the threaded portion 26.

To attach my invention to an ordinary collapsible tube as shown in Fig. 2, I first 15 remove the usual cap 16 therefrom and insert the tube, the nozzle end uppermost within the protective sheaf 22 through the open lower end 23 until the nozzle 12 thereof protrudes through the central nozzle opening 21, the 20 cap member 24 is then suitably secured to said nozzle by threading it on the threads 14 of said nozzle until the lower end 30 thereof abuts the rigid top member 20 of said sheaf 18 when said lower end 30 will function to securely bind the sheaf 18 to said tube. When 25 it is desired to dispense the contents of the tube, the rotatable member 36 is merely rotated relative to said threaded member 26 until an open portion 50 of the side wall 38 30 thereof is brought into alignment with the dispensing slot 32 in said threaded portion when on suitable squeezing of the tube as shown in Fig. 1 the contents 25 of the tube will flow therefrom.

35 It is thus apparent that I have provided a novel type of protective sheaf or covering for collapsible tubes which not only protects it but enhances the ornamental appearance thereof with a novel type of cap member, the 40 cap member functioning to secure in addition the sheaf to said tube.

It is understood that my invention is not limited to the specific embodiment shown and that various deviations may be made therefrom without departing from the spirit and 45 scope of the appended claims.

What I claim is:

1. A device for use with a collapsible tube having an externally threaded central dispensing nozzle on the upper end thereof, comprising a protective sheaf for said tube comprising a rigid top member having a central nozzle opening and adapted to abut the top 50 of said tube exteriorly of said nozzle and a member of flexible material attached to said top member and adapted to enclose the sides of said tube and having an open lower end for insertion of the tube therein and a cap member for said tube comprising an internally threaded portion adapted to be threaded onto said nozzle, said portion having a dispensing slot in the side thereof above said nozzle and a portion having a side wall surrounding said threaded portion rotatably secured to said threaded portion having a portion of the side wall thereof open to dispense the contents of the collapsible tube through the channel formed when the open portion 115 of the side wall of the rotatable portion is brought into alignment with the slot in the threaded portion.

2. A device for use with a collapsible tube having a side wall surrounding said threaded portion rotatably secured to said threaded portion having a portion of side wall thereof open to dispense the contents of the collapsible tube through the channel formed when the open portion of the side wall of the rotatable portion is brought into alignment with the slot in the threaded portion. 70

2. A device for use with a collapsible tube having an externally threaded central dispensing nozzle on the upper end thereof, comprising a protective sheaf for said tube comprising a rigid top member having a central nozzle opening and adapted to abut the top 75 of said tube exteriorly of said nozzle and a member of woven wire attached to said top member and adapted to enclose the sides of said tube and having an open lower end for insertion of the tube therein and a cap member for said tube comprising an internally threaded portion adapted to be threaded onto said nozzle to have the lower end thereof abut the top sheaf member around said nozzle to secure said sheaf to said tube, said portion having a dispensing slot in the side thereof 80 above said nozzle and a portion having a side wall surrounding said threaded portion rotatably secured to said threaded portion having a portion of the side wall thereof open to dispense the contents of the collapsible tube 85 through the channel formed when the open portion of the side wall of the rotatable portion is brought into alignment with the slot in the threaded portion.

3. A device for use with a collapsible tube having an externally threaded central dispensing nozzle on the upper end thereof, comprising a protective sheaf for said tube comprising a rigid top member having a central nozzle opening and adapted to abut the top 100 of said tube exteriorly of said nozzle and a member of flexible material attached to said top member and adapted to enclose the sides of said tube and having an open lower end for insertion of the tube therein and a cap member for said tube comprising an internally threaded portion adapted to be threaded onto said nozzle, said portion having a dispensing slot in the side thereof above said nozzle and a portion having a side wall surrounding said threaded portion rotatably secured to said threaded portion having a portion of the side wall thereof open to dispense the contents of the collapsible tube through the channel formed when the open portion 110 of the side wall of the rotatable portion is brought into alignment with the slot in the threaded portion. 115

4. A device for use with a collapsible tube having an externally threaded central dispensing nozzle on the upper end thereof, comprising a protective sheaf for said tube comprising a rigid top member having a central nozzle opening and adapted to abut the top 120 of said tube exteriorly of said nozzle and a 125

flexible metallic member attached to said top member and adapted to enclose the sides of said tube and having an open lower end for insertion of the tube therein and a cap member for said tube comprising an internally threaded portion adapted to be threaded onto said nozzle said portion having a dispersing slot in the side thereof above said nozzle and a portion having a side wall surrounding said threaded portion rotatably secured to said threaded portion, said portion having a portion of the side wall thereof open to dispense the contents of the collapsible tube through the channel formed when the open portion of the side wall of the rotatable portion is brought into alignment with the slot in the threaded portion.

5. A protective sheaf adapted to receive and enclose a collapsible tube, comprising a rigid top member having a central nozzle opening adapted to abut the top of said tube exteriorly of its nozzle and a member of freely flexible material attached to said cap member of a size and shape to compactly 20 enclose the sides of said tube and having an open lower end for insertion of the tube therein.

6. A protective sheaf adapted to receive and enclose a collapsible tube, comprising a rigid top member having a central nozzle opening adapted to abut the top of said tube exteriorly of its nozzle and a member of freely flexible metallic material attached to said cap member, of a size and shape to compactly 25 enclose the sides of said tube and having an open lower end for insertion of the tube therein.

7. A device for use with a collapsible tube having a central dispensing nozzle in the upper end thereof, comprising a protective sheaf for said tube, comprising a rigid top member having a central nozzle opening adapted to abut the top of said tube exteriorly of said nozzle and a member of flexible material attached to said top member and adapted to enclose the sides of said tube and having an open lower end for insertion of the tube therein and a cap member for said tube comprising a portion adapted to be attached on to said nozzle to have the lower end thereof abut the top sheaf member around said nozzle to secure said sheaf to said tube, said portion having a dispensing slot in the side thereof above said nozzle and a dispensing cap having a side wall surrounding said portion rotatably secured to said portion, said rotatable portion also having a portion of the side wall thereof open to dispense the contents of the collapsible tube 50 through the channel formed when the open portion of the side wall of the rotatable portion is brought into alignment with the slot in the slotted portion.

In testimony whereof I affix my signature.
65 JAMES G. JOHNSTON.
